UNITED STATES PATENT OFFICE

2,461,306

OSCILLATOR-AMPLIFIER RADIO CIRCUITS

John J. Antalek, Chicago, Ill., assignor to The Rauland Corporation, Chicago, Ill., a corporation of Illinois

Application May 31, 1943, Serial No. 489,235

7 Claims. (Cl. 250—36)

1

This invention relates to electronic tubes and the circuits connected thereto, especially relating to devices employed in connection with radio reception and transmission.

One purpose of this invention is to provide circuits utilizing a single electronic tube, in which circuits such tube will perform a plurality of functions, such as the functions which hitherto have required the use of more than one electronic tube.

Another purpose of this invention is to provide a radio telegraph or telephone receiver in which the total number of electronic tubes required is reduced below that hitherto found necessary, more particularly in connection with radio receivers of the superheterodyne type.

Still another purpose of this invention is to provide a radio receiver in which an electronic tube normally functioning to cooperate with the remainder of the receiver for the purposes of signal reception, will likewise function as a source of electrical oscillations of predetermined frequency, which oscillations may be utilized to calibrate the receiver as a whole.

A still further purpose of this invention is to provide a circuit in which a single electronic tube functions simultaneously as an audio frequency amplifier and as a radio frequency oscillator.

Yet another purpose of this invention is to provide a radio receiving circuit in which an electronic tube functioning as an audio frequency amplifier, obtains its grid bias voltage by simultaneously functioning as an oscillator at a superaudible frequency, the superaudible oscillations giving rise to the bias required by the tube as an audio frequency amplifier.

Another purpose of this invention is to provide a radio receiving device in which a single electronic tube performs the simultaneous functions of an oscillator producing a beat note with an incoming signal, of a diode type detector of such signal, and of an audio amplifier of the signal, after detection.

A still further object of this invention is to provide, in a superheterodyne radio receiver, a circuit in which a single electronic tube functions simultaneously as an amplifier of intermediate frequencies and of audio frequencies, thereby allowing the elimination of at least one electronic tube hitherto employed to fulfill only one of these functions.

A yet further object of this invention is to provide a radio transmitting circuit in which a single electronic tube functions both as an oscillator,

2

with or without crystal control, and as a speech amplifying tube.

Still further objects and advantages of this invention will be apparent to those skilled in the art, among which advantages are those of economy of material, space and weight, in radio telegraph or telephone transmitters and receivers. Such advantages are of particular importance in connection with portable radio transmitting and receiving equipment.

Reference is now made to the accompanying drawings, where

Fig. 1 is a schematic diagram showing a portion of a complete circuit, according to this invention, wherein a single electronic tube of the multi-element type, performs the function of a detector, an audio frequency amplifier and a crystal controlled oscillator.

Fig. 2A is a schematic representation of a portion of a circuit wherein a single triode is used simultaneously as a high frequency oscillator and as an audio frequency amplifier.

Fig. 2B is a schematic drawing of a portion of a circuit, utilizing a single tetrode to accomplish the same results given by the triode of Fig. 2A.

Fig. 3A is a schematic representation of a portion of the circuit of a radio receiver of the superheterodyne type, illustrating the use, according to this invention, of a single electronic tube of the multi-element type as an amplifier of received signals at an intermediate frequency, as a detector of such amplified signals, and likewise as an amplifier at audio frequency of the thus detected signals.

Fig. 3B is a schematic showing of a modified form of the circuit of Fig. 3A.

Fig. 4A is a schematic showing of a portion of a circuit wherein a single tetrode is simultaneously used, according to this invention, as an audio frequency amplifier and as a crystal controlled oscillator.

Fig. 4B is a schematic showing of a modification of the circuit of Fig. 4A, in which a variable frequency oscillator circuit is substituted for the crystal controlled oscillator circuit of Fig. 4A.

Fig. 5 is a schematic showing of a radio telephone transmitter embodying certain principles of this invention, including a crystal controlled oscillator circuit.

Fig. 6 shows schematically a modified form of a portion of the circuit of Fig. 5, employing an oscillator circuit wherein the frequency is determined by the electrical constants of a coil and a condenser, in lieu of the crystal control shown in Fig. 5.

Fig. 7 shows a circuit using a single tube as a beat frequency oscillator, a detector and an audio amplifier.

Referring now to Fig. 1, there is here shown the portion of a superheterodyne receiver immediately following the portion thereof where amplification has been accomplished at an intermediate frequency. The input transformer shown at 100 may conveniently have its primary 101 tuned by condenser 102 to the intermediate frequency employed by the receiver, while the secondary 103 is similarly tuned by condenser 104, to the same frequency. The intermediate frequency is applied through lead 105 to the diode plates 106, 106 of electronic tube 107. The intermediate frequency return to ground is made through by-pass condenser 108, and cathode 109 of tube 107 is likewise grounded. Resistor 110 acts as a filter resistor for the intermediate frequency, in connection with by-pass condenser 111, connected to the ground at one side. Resistor 112 is likewise shunted to ground across condenser 111 and constitutes a potentiometer type volume control by virtue of the variable connection point 113 through which the rectified and filtered audio frequencies are taken off, via audio grid coupling condenser 114, and applied through radio frequency filter resistor 115 to control grid 116 of tube 107. The potential of grid 116 is maintained via grid leak resistor 117, connected from the lower end of resistor 115 to the ground.

The amplified audio frequency output of tube 107 is taken off from the anode 118 thereof and supplied to the audio frequency output terminals 119, 119, via audio frequency coupling condenser 120 and from ground connection 121. The D. C. operating energy for anode 118 may be derived from any suitable source such as that indicated at 122, via anode load resistor 123, the anode likewise being connected to ground through radio frequency by-pass condenser 123'.

The screen grid 124 of tube 107, is kept at a suitable D. C. potential by connection to the source indicated at 122, via voltage dropping resistor 125, being effectively maintained at ground potential, with respect to A. C., by means of audio frequency by-pass condenser 126. Likewise interposed between by-pass condenser 126 and screen grid 124, is inductance 127, of which a portion may be shunted out by means of switch 128. Shunt connection 129 also is extended from screen grid 124, via output coupling condenser 130. This shunt output connection serves as a means whereby the oscillatory energy developed, as hereinafter explained, by tube 107, may be applied to another desired purpose, for example to the input of a radio frequency tube located at a prior point of the receiving circuit.

The operation of tube 107 as an oscillator, is brought about as a connection of a piezo-electric crystal 131 between control grid 116 and ground point 132. Inductance 127 should be so designed that its resonant frequency, when connected as shown, will match that as shown of piezo-electric crystal 131, or some harmonic thereof. The closure of switch 128 will destroy such resonant relationship, and thereby will cause tube 107 to cease functioning as an oscillator, if so desired.

The output of tube 107 functioning as an oscillator may be used for several purposes. If connected as above-described, to an earlier portion of the receiver, or as indicated by dotted line 140, to the primary of the last intermediate frequency tube of the receiver, it may be employed as a

producer of the beat frequency used in the intermediate frequency amplifier stages of the receiver. Alternatively, the various harmonics of crystal 131 may be fed back into the receiver and employed as calibration frequencies therefor.

Still another mode of employment of the circuit of Fig. 1, contemplates that the crystal oscillator controlled section of tube 107 shall be arranged to deliver an oscillatory output at a frequency approximating that employed in the intermediate stages of the receiver, so that an audio frequency beat note may be produced by suitable combination of these two frequencies, thus enabling audio frequency reception of unmodulated continuous wave signals. For this last mentioned application, it may be found expeditious to substitute for the crystal control of frequency, an oscillatory circuit employing actual physical inductance and capacity, as will be understood by those skilled in the art.

Making reference now to Fig. 2A, the electronic tube 200 has its control grid 201 connected via radio frequency choke coil 202, to the secondary winding 203 of audio frequency input transformer 204, primary winding 205, of this transformer, being supplied with the audio frequency input signals. Audio frequency by-pass condenser 206 is connected to the ground and constitutes a portion of the return path for the audio frequency signals to the cathode 207 of tube 200. The static potential of control grid 201 is maintained by grid leak resistor 208, also connected to the ground.

The audio frequency output of tube 200 is conveyed from the anode 209 thereof, to primary winding 210 of output transformer 211, the audio frequency output of the entire amplifier being drawn from secondary winding 212 of transformer 211. Radio frequency by-pass condenser 213 is connected directly from anode 209 to the ground and functions to prevent the development of unwanted radio frequency potentials across winding 210, the origin of such potentials being hereinafter explained.

The cathode 207 of tube 200 is connected to an intermediate point of inductance 214, this inductance functioning to determine production of oscillations by tube 200. The lower end of inductance 214 is grounded, and the upper end thereof is connected to control grid 201 via oscillator grid condenser 215. It will be apparent to those skilled in the art that this mode of connecting the grid, anode and cathode, respectively, of tube 200, to inductance 214, constitutes a well-known type of oscillatory circuit employed in connection with electronic tubes.

When tube 200 is set into oscillation by reason of the oscillatory circuit connection just described, there will be developed across resistor 208, a D. C. potential which will serve to maintain control grid 201 at a suitable D. C. potential, for the proper functioning of tube 200 as an audio frequency amplifier. The reason for the presence of radio frequency by-pass condenser 213 will now fully be apparent.

In Fig. 2B the audio frequency input passes through grid coupling condenser 250 to control grid 251 of tetrode 252, via radio frequency filter resistor 253. Control grid 251 is likewise connected to ground via grid leak resistor 254. Anode 255 of tube 252 is likewise grounded with respect to radio frequency, by means of by-pass condenser 256 and derives its operating energy from any suitable source, such as that indicated at B+, via primary winding 257 of audio fre-

quency output transformer 258, from the secondary winding 259 of which is delivered such audio frequency output. A voltage dropping resistor 260 is connected between the source of energy just described and the screen grid 261 of tube 252, this screen grid being by-passed to ground via condenser 262.

The oscillatory function of tube 252 is brought about by the connection of the cathode 263 thereof to an intermediate point on inductance 264, this inductance being grounded at its lower end and connected at its upper end via oscillator grid condenser 265 to control grid 251 of the tube. Since the dual functioning of tetrode 252 and the maintenance of control grid 251 at the proper operative D. C. potential by means of resistor 254, are brought about in the same fashion as already described in connection with Fig. 2A, a detailed recitation thereof is thought unnecessary.

Referring now to Fig. 3A, the signal-bearing currents received at antenna 300 and ground 301 pass through the primary winding 302 of the antenna coupling transformer 303, the secondary winding 304 of which transformer is suitably tuned by variable condenser 305. One end of secondary 304 is connected to control grid 306 of mixer or converter tube 307, while the other end of secondary 304 is grounded via by-pass condenser 308. Resistor 309 affords a bias for grid 306 and is connected so as to bring about automatic volume control, as well known in the art. At 310 is indicated an oscillator coil tuned by a variable condenser 311 which may conveniently be ganged with variable condenser 305, so as to allow single tuning control of the receiver. The oscillator circuit formed by elements 310 and 311 is coupled via oscillator grid condenser 312 to grid 313 of tube 307, the bias potential of grid 313 being established by oscillator grid resistor 314. The cathode 315 of tube 307 is connected to an intermediate point 316 on inductance 310, so as to form suitable connections for producing oscillations. The output of mixer tube 307 is taken from the anode 317 thereof, and transformer 318 has the primary winding 319 connected in series with the anode circuit of tube 307. This primary winding is tuned to a suitable intermediate frequency equivalent to the beat frequency produced by tube 307 and its associated circuits, by means of condenser 320. The anode supply circuit extends from the lower portion of transformer 318 to the point indicated by B+, indicating any suitable source of D. C. high potential. The remaining grids 321 and 322 of tube 307 may conveniently obtain their voltage supply from the same source which feeds the anode of the tube, via a voltage dropping resistor 323, being suitably by-passed to ground via condenser 324.

The intermediate frequency signal bearing energy derived from tube 307 and the associated circuits just described, will then appear in secondary winding 325 of IF transformer 318, this last winding being likewise tuned by condenser 326 to a frequency corresponding to that to which the primary winding of transformer 318 is tuned. Secondary winding 325 is connected at one end to control grid 327 of a multi-element tube 328, and is connected at the other end to ground via IF by-pass condenser 329. Tube 328 has the cathode 330 grounded and the screen grid 331 thereof may receive its energy from the common supply indicated at B+, through a suitable voltage dropping resistor 332 and is by-passed to ground via condenser 333. The IF signals fed to grid 327

will be amplified by tube 328 and the amplified signals appearing on the anode 334 of this tube are fed into primary winding 335 of a second intermediate frequency transformer 336, this primary being tuned by condenser 337 to the frequency of such IF signals and being by-passed to ground via condenser 337. Secondary winding 338 of transformer 336 is likewise tuned by condenser 339 and feeds element 340 of tube 328, this tube element functioning to afford diode detector action. The low frequency signals resulting from such detecting action appear across load resistor 340, the usual smoothing or intermediate frequency by-pass condenser 342 and IF filter resistor 341 being connected from the lower end of winding 338 to the ground, the path for resistor 341 being via load resistor 340.

The audio frequency signals which have resulted from the IF amplification and detection just described will then feed back via conductor 342' to the lower end of secondary winding 325 of transformer 318. Due to the relatively low impedance presented by this winding to audio frequency currents, such signals appear, practically unreduced in intensity, upon control grid 327 of tube 328. In this manner, the amplifier section of tube 328 will perform the additional function of amplifying the audio frequency currents fed into grid 327, while at the same time it is amplifying the IF currents, as previously described.

The amplified audio output of tube 328 appears across the anode load resistor 343. It will be noted that the by-passing action of condenser 337' allows the intermediate frequency signals fed to primary winding 335 of transformer 336, to pass directly to ground without being weakened by passage through the resistor 343, just described. From the junction point between the upper end of resistor 343, which resistor likewise serves to supply anode potential to tube 328, and the lower end of primary winding 335, is taken a lead 344, through which the ultimate amplified audio frequency output of tube 328 passes, via audio frequency coupling condenser 345 and is fed to volume control 346, of the potentiometer type, ultimately reaching ground through conductor 347.

At 348, is shown an output or power amplifier tube which performs only the single function of handling the audio frequency signals fed to the grid 349 thereof from volume control 346. Tube 348 has the grid bias suitably determined by cathode resistor 350, having by-pass condenser 351 connected in shunt therewith. Screen grid 352 and anode 353 of tube 348, may conveniently receive their potential from a common source indicated at B+. The audio frequency output of tube 348 is fed to the primary winding 354 of output transformer 355, from the secondary winding 356 of which such audio frequency output may be taken.

In the receiver just described, the plural functioning of tube 328 allows the elimination of the intermediate frequency amplifier tube which has hitherto been found necessary, thus allowing the receiver to be built with greater economy of material, space and weight.

Referring now to Fig. 3B, the antenna circuit and the mixer tube circuits, including the input circuit to tube 328, are shown respectively as identical with the like portions of Fig. 3A and bear identical reference numerals. The diode element 340 of tube 328 likewise is fed from an intermediate frequency transformer 336, having a tuned secondary circuit 338, 339, in the same

fashion as indicated in Fig. 3A. This secondary circuit is by-passed for intermediate frequency to ground by condenser 342, and an intermediate frequency filter resistor 341 is placed in series with the diode load resistor 330, the audio frequency output appearing across resistor 330. The tuned primary circuit 335, 337, of this transformer is placed in series with the circuit of screen grid 331 of the tube, instead of being placed in series with the anode 334 thereof. Voltage dropping resistor 332 is connected between the lower end of this tuned primary circuit and the source of high voltage which feeds the anode circuit of tube 328, but by-pass resistor 333, connected directly between the lower end of the tuned primary circuit and the ground, serves to prevent loss of intermediate frequency energy in resistor 332. The audio frequency output from the anode circuit of tube 328 appears across plate load resistor 343, which, in this case, is directly coupled at its upper end to anode 334 and by-passed with respect to intermediate frequencies, directly to ground by condenser 337'. The lower end of resistor 343 is connected directly to the source of anode potential by means of conductor 343'. The amplifier audio frequency output of tube 328 is delivered through stopping condenser 345 and may be withdrawn between the open side of this condenser and the ground as indicated in Fig. 3B by the legend "AF output." In Fig. 3B the final output tube corresponding to tube 348 of Fig. 3A, is omitted, since its function is identical with that indicated in Fig. 3A.

The placing of transformer 356, feeding intermediate frequency energy to the diode portion of tube 328, causes this tube to function as a triode amplifier of intermediate frequency energy, while the fact that the audio frequency output is drawn from anode 334, causes the tube to function as a tetrode, with respect to the audio frequency amplification. This mode of connection results in less gain at the intermediate frequency. However, the oscillation of the anode load circuit from the intermediate frequency circuits connected to this tube, allows the use of a larger size anode load resistor as element 343, thus rendering possible a greater audio frequency amplification, without causing any reduction of the intermediate frequency gain. In practice it has been found that the overall gain of the circuit indicated in 3B is somewhat less than that of the circuit indicated in 3A, but the isolation of the audio frequency output has been found desirable in certain applications.

Referring now to Fig. 4A, tube 400 has connected between control grid 401 and anode 402, a crystal 403, which causes the tube to function according to the type of the so-called Pierce oscillator. At the same time the tube receives an audio frequency input from terminals 404, through coupling condenser 405 and resistor 406, the grid 401 being maintained at a suitable potential by means of a grid leak 407. The anode 402 is isolated by radio frequency choke coil 408, but the audio frequency output passes through this choke coil and appears across the primary 409 of output transformer 410, available across the secondary winding 411 of this transformer. A suitable source of anode energy is indicated at B+ and this same source may conveniently be fed through voltage dropping resistor 412, to screen grid 413 of the tube, a suitable by-pass condenser 414 being provided.

In Fig. 4B is shown tube 400 with a similar

audio frequency feed circuit, as indicated by like reference numerals. In this case, the radio frequency oscillation of the tube is brought about by connecting the cathode 450 to a suitable intermediate point 451 of inductance 452, the upper side of this inductance being coupled by oscillation condenser 453 to grid 401, while the lower end of the inductance is grounded at 454.

A variable condenser 455 is shunted across coil 452 and serves to determine the frequency of oscillation of the circuit. In this case, there is indicated a resistance coupled output circuit from anode 402 of the tube, including by-pass condenser 456, load resistor 457, and coupling condenser 458, the audio frequency output being available between the free side of condenser 458 and the ground, as indicated on the drawing.

The combination audio frequency amplifier and radio frequency oscillators, as shown in Figs. 4A or 4B may have their radio frequency output utilized for any convenient purpose, such as to feed a mixer tube, as a beat frequency oscillator, and so forth, as previously mentioned in connection with the circuit of Fig. 1.

In Fig. 5 is indicated a radio telephone transmitter, where microphone 500 serves to modulate energy received from battery 501 and is coupled via input transformer 502 and radio frequency choke coil 503, to the grid 504 of tube 505. A crystal 506 is connected between grid 504 and the ground while the return D. C. path of the grid is completed through biasing resistor 507, shunted by by-pass condenser 508. The operation of this biasing resistor, when tube 505 is in oscillation at a frequency determined by crystal 506, is similar to that already described in connection with Fig. 2A, the higher frequency oscillations thus creating a suitable D. C. bias for tube 505.

The screen grid 509 of the tube is employed as an anode, and variable capacity 510, shunted across inductance 511, constitutes the oscillatory tank circuit, tuned to the frequency of crystal 506. This constitutes a tuned grid-tuned plate oscillator, the output of which is coupled via grid coupling condenser 512, to power amplifier tube 513, the grid 514 of this tube being maintained at a suitable potential by grid leak resistor 515. Tube 513 is anode modulated by the audio frequency output derived from the anode 516 of tube 505, this anode being suitably by-passed with respect to radio frequency by means of condenser 517, while the audio frequency output thereof is impressed via modulation transformer 518, and the anode tank coil 519, connected to the anode 520 of the power amplifier tube 513, this anode tank coil being tuned by variable condenser 521 to the frequency of crystal 506. A suitable radio frequency by-pass condenser 522 shunts the the secondary winding of transformer 518.

The voltage dropping resistors, by-pass condensers and high voltage connections of the screen grids of tubes 505 and 513 are indicated in conventional fashion, and a detailed description thereof is thought to be unnecessary. A complete radio telephone transmitter is thus obtained, with the employment of only two electronic tubes.

Referring now to Fig. 6, there is here indicated an alternative arrangement of tube 505, in which a self-excited oscillator circuit takes the place of the crystal 506 of Fig. 5. The input transformer 502, is connected to control grid 504 via the lower portion of a split inductance 600, indicated by the dotted lines in Fig. 6. The upper

portion of inductance 600 is introduced in series with the circuit connected to the screen grid 509 of tube 505, and is tuned by condenser 601, thus constituting the tuned tank circuit determining the radio frequency period of the circuit. A suitable radio frequency by-pass condenser 602 is connected from the upper end of the secondary of transformer 502, to the ground, thus affording a direct path for the radio frequency currents circulating through the lower portion of split inductance 600.

The radio frequency grid coupling condenser 512, by-pass condenser 517 and modulation transformer 518 are connected in the same fashion as shown in Fig. 5 and it is thought unnecessary again to indicate the radio frequency power amplifier tube and antenna connections, since these may be made identical with those shown in Fig. 5.

Making reference now to Fig. 7, there is here shown a portion of a superheterodyne type radio receiver, including the last stage of intermediate frequency amplification, together with the input and output coupling devices therefor. Likewise there is shown in this figure a multi-element electronic tube connected both to the input and the output of this final stage of intermediate frequency amplification. This last-mentioned tube functions simultaneously as an oscillator, producing current of a frequency which will beat with the intermediate frequency, as a diode type detector and as a high gain audio frequency amplifier.

Tube 700 is shown as of the tetrode type, but it is understood that this tube may be of any other type suitable for intermediate frequency amplification, for example a pentode, and changes in the circuit here shown, in order to adapt it for the use of such other type tube, will be apparent to those skilled in the art. Cathode 701 of tube 700 is kept at a suitable operating potential by means of bias resistor 702, by-passed by condenser 703. Heater 704 may be fed with energy from any suitable source (not shown). The control grid 705 is kept at a potential dependent upon the potential of conductor 706, as fed through filter resistors 707 and 708. The use of such variable potential in order to secure automatic volume control is well known in the art and a detailed description thereof is therefore thought to be unnecessary. Input transformer 708 is shown with a primary winding 709, suitably tuned by a capacity 710, while secondary winding 711 is likewise tuned by capacity 712. The output of transformer 708 is fed between control grid 705 and the ground, the latter connection being made via intermediate frequency by-pass condenser 713. Screen grid 714 is fed from a suitable high potential source indicated at 715 by the legend B+, through voltage dropping resistor 716 and is by-passed to ground by condenser 717.

The amplified output of tube 700 is taken from the anode 718 thereof and fed to primary winding 719, suitably tuned by condenser 720, of intermediate frequency output transformer 721. Secondary winding 722, of transformer 721, also suitably tuned by capacity 723, is connected between the detector element 724 of multi-element tube 725, and the ground, the latter connection being made via intermediate frequency by-pass condenser 726. The rectified output of the detector portion of tube 725 passes through diode filter resistor 727, by-passed to ground by another intermediate frequency condenser 728, and to resistor 729. This last resistor 729 is connected at its lower extremity to the ground and may

conveniently be provided with a movable contact 730, functioning as a volume control, and feeding audio frequency energy through coupling condenser 731 to the audio frequency amplifier section input of tube 725.

Tube 725 has the cathode 732 thereof grounded and cathode heater 733 may be fed from any suitable source of energy (not shown). The audio frequency input for tube 725, obtained via audio frequency coupling condenser 731, is fed through radio frequency isolating resistor 734, to control grid 735, the potential of this control grid being maintained at a suitable value via grid leak resistor 736, connected from the lower end of resistor 734 to the ground.

The amplified audio frequency output of tube 725 is taken from the anode 737 thereof, and appears across output terminals 738, as indicated by the legend appended thereto. Anode 737 is fed from any suitable source of energy, as indicated at 739 by the legend B+, through plate load resistor 740. Any radio frequency components of the current taken from anode 737 are by-passed to ground by a suitable condenser 741.

The oscillation generating action of tube 725 is brought about between control grid 735 and screen grid 742. A preferably variable inductance 743, tuned by a shunt capacity 744 to the intermediate frequency, or to some sub-harmonic thereof, is connected directly to screen grid 742 and via coupling condenser 745 to control grid 735. The supply of energy for screen grid 742 may conveniently be obtained from the same source as the supply for the anode thereof, as indicated at 746, via voltage dropping resistor 747, by-passed to ground with respect both to radio and audio frequencies by condenser 748. The direct current voltage applied via resistor 747 is connected to an intermediate point 749 upon inductance 743. A switch 750, grounded at one side, serves optionally to connect screen grid 742 to ground, via a relatively high capacity condenser 751. When switch 750 is closed, the connection of screen grid 742 to ground serves effectively to short-circuit a portion of inductance 743, in as far as intermediate frequency oscillations are concerned. Therefore, the closure of this switch serves to prevent the production of such oscillations by tube 725, while at the same time allowing the other functions of this tube to continue uninterruptedly.

The intermediate frequency energy appearing at the upper end of inductance 743 is transmitted via conductor 752 and voltage coupling condenser 753, to the upper end of secondary winding 711 of transformer 708, as shown by the connection at point 754. The intermediate frequency, the period of which is determined by the constants of inductance 743 and capacity 744, is suitably adjusted, as by the variation of the value of inductance 743, so as to be sufficiently different from that of the intermediate frequency due to an incoming signal and appearing at winding 711, so that a beat note, usually of an audio frequency, will be produced by the interaction of these two intermediate frequencies. The use of such beat frequency for the reception of unmodulated continuous wave signals is well known in the art, while other possible applications of such beat frequency will be apparent to those skilled in the art.

The functioning of tube 725 as detector and audio frequency oscillator corresponds to the manner in which tube 167 of Fig. 1 functions and accordingly it is thought unnecessary here to

11

repeat in detail such other functions performed by tube 725.

What is claimed is:

1. In a combination amplifier and oscillator, an electronic tube having cathode, control grid and anode, circuit means oscillating at a frequency range outside the audio frequency range, said circuit means comprising an inductance connected at the ends thereof between control grid and anode, and connected at an intermediate point to the cathode, means for feeding audio frequency energy to said control grid, means for withdrawing audio frequency energy from the anode, grid biasing means comprising a resistor connected between said grid and ground, and a capacity bypassing said resistor for said audio frequency energy, and establishing across said resistor a bias potential.

2. In combination, a tetrode having a cathode, control grid, screen grid and anode, an inductance connected at the ends thereof between control grid and anode and tapped at an intermediate point to the cathode, a coupling condenser and filter resistor in series with said control grid, means for feeding audio frequency energy to the free end of said coupling condenser, means for withdrawing audio frequency energy from said anode and a grid biasing resistor connected between the common point of said coupling condenser and said filter resistor and ground, to produce oscillations outside of the audio frequency range and establishing a potential across said grid biasing resistor, oscillations being filtered out by said filter resistor from the audio frequency energy feeding means.

3. A device according to claim 1, in which the audio energy feeding means comprise a first transformer and the audio energy withdrawing means comprises a second transformer and also including a condenser effectively in shunt with the primary of said second transformer, so as to bypass said primary as to oscillatory energy.

4. In a combined oscillator and amplifier, a multi-element electronic tube having cathode, control grid and anode, means for feeding audio frequency energy to said control grid, means for withdrawing amplified audio frequency energy from said anode, circuit means oscillating at a frequency range outside the audio frequency range and connected to said control grid and said anode to bias said grid, and filter means connected respectively to said control grid and said anode, whereby oscillatory energy is substantially prevented from reaching said audio fre-

12

quency feeding and withdrawing means, and means for energizing said tube.

5. A device according to claim 4 in which said circuit means comprise a tuned tank circuit connected at the end thereof effectively between said control grid and said anode and connected at an intermediate point to said cathode.

6. In combination, an electronic tube including input and output electrodes, circuit means for feeding audio frequency energy to an input electrode, circuit means for withdrawing amplified audio frequency energy from an output electrode, means for biasing said input electrode, said biasing means including circuit means connected thereto and oscillating at a super-audible frequency, and a biasing resistor also connected thereto, and filter means interposed between input electrode and audio frequency feeding circuit means and between output electrode and audio frequency withdrawing circuit means, respectively, said filter means passing said audio frequency, whereby said tube functions simultaneously as an oscillator and as an audio frequency amplifier.

7. In combination, an electronic tube having cathode, control grid and anode, and means for energizing said tube, oscillating circuit means comprising an inductance connected from control grid to anode and tapped to the cathode, audio frequency feeding means connected to said control grid, audio frequency output means connected to said anode, a grid bias resistor connected between said control grid and ground, and means substantially isolating said resistor from the oscillating currents, whereby the action of said oscillating circuit means upon said control grid establishes a direct current potential drop across said grid bias resistor and thereby biases said tube as an audio frequency amplifier.
